Heidi L. Eisenhut

(57) **CLAIM**

The ornamental design for an arbor for cutting blades, as shown and described.

DESCRIPTION

FIG. 1 is a top, right perspective view of an arbor for cutting blades of the present invention;

FIG. 2 is a top, left perspective view of the arbor for cutting blades of FIG. 1;

FIG. 3 is a first side elevation view of the arbor for cutting blades of FIG. 1;

FIG. 4 is a second side elevation view of the arbor for cutting blades of FIG. 1; and,

FIG. 5 is a top plan view of a cutting blade with the arbor for cutting blades of FIG. 1.

The broken line showing the outside edge of the arbor for cutting blades is included for the purpose of illustrating a feature that forms no part of the claimed design.

1 Claim, 2 Drawing Sheets
